UNITED STATES PATENT OFFICE

91,976

DESIGN FOR A COMBINED PENCIL AND LETTER OPENER

Frank C. Deli, Chicago, Ill., assignor to Auto-point Company, Chicago, Ill., a corporation of Illinois

Application February 8, 1934, Serial No. 50,675

Term of patent 3½ years

To all whom it may concern:

Be it known that I, FRANK C. DELI, a citizen of the United States, residing at Chicago, in the county of Cook and State of Illinois, have invented a new, original, and ornamental Design for a Combined Pencil and Letter Opener, of which the following is a specification, reference being had to the accompanying drawings, forming part thereof.

Fig. 1 is a side elevation of a combined pencil and letter opener showing my new design, and Fig. 2 is a similar view taken at right angles to that of Fig. 1.

I claim:

The ornamental design for a combined pencil and letter opener, as shown.

FRANK C. DELI.
